Willis E. Green, 6216 Main Ave.,
Orangevale, Calif. 95662

Filed Aug. 11, 1970, Ser. No. 24,424

Term of patent 14 years

Int. Cl. D22—05
U.S. Cl. D22—22

FIG. 1 is a front perspective view of a fishing pole holder with the spring-loaded, earth-penetrating mounting spike with fishhook disgorge tip in extended position, showing my new design;

FIG. 2 is a rear perspective view of FIG. 1;

FIG. 3 is a view comparable to FIG. 1 but with the mounting spike with hook disgorge tip in retracted position, and showing the upwardly facing fishhook sharpening surface exposed;

FIG. 4 is a top plan view; and,

FIG. 5 is a bottom plan view.

I claim:

The ornamental design for a fishing pole holder, as shown and described.
